L. KANOWITZ

PROTECTIVE COVERING DEVICE

Filed June 2 1926

Patented Apr. 17, 1928.

1,666,601

UNITED STATES PATENT OFFICE.

LENA KANOWITZ, OF NEW YORK, N. Y.

PROTECTIVE COVERING DEVICE.

Application filed June 2, 1926. Serial No. 113,121.

My invention relates to protective coverings and refers particularly to such coverings of a character that will allow the passage of air and prevent the passage of insects therethrough.

Among the objects of my invention is a device which can be readily positioned over a recumbent person to protect the person from the attacks of insects while allowing free access of air.

A device of this character should be of such construction that the material will not rest upon the face of the user and that it will not be accidentally displaced from its desired position.

The usual method of employing netting, and similar material, for this purpose, is to erect a support behind the user's head and to throw, or drape, the netting over this support, in order that it may not touch the face of the user, and then allow the netting to fall over both sides of the couch, or bed, upon which the user reclines.

As the support thus employed is not a part of the netting, it is frequently inconvenient, and at times impossible, to so supply and position it as to render it effective.

Further, when the netting is allowed to simply drape over the sides of the couch, the movement of the user is liable to dislodge it, thus rendering the netting ineffective for the purposes for which it is intended.

The device of my invention overcomes the above enumerated and other inconveniences and ineffectiveness and presents a device which in itself acts as a support for the netting and also prevents its accidental displacement, which valuable attributes will be evident upon a consideration of my specification and its accompanying drawings.

In the accompanying drawings, illustrating modifications of the device of my invention, similar parts are designated by similar numerals.

Figure 1 is a vertical cross-section of one form of my device as applied to a baby carriage.

Figure 2 is a perspective view of a modified form of my device adapted by application to a recumbent person, partly broken away.

Figure 3 is a cross section through the line 3-3 of Figure 2.

Figure 4 is a front view of the netting support of Figure 1.

Figure 5 is a broken perspective view of

the lower end of my device shown in Figure 1.

The device of my invention shown particularly in Figures 1 and 5 comprises a support having the base 10 through which is an opening, or recess 11. The two ends of a resilient wire, or band, head-piece 12 are slidable within the opening 11. It is evident that by inserting, or withdrawing, the head-piece 12, the contour of the loop thus formed may be varied as shown in Figure 4, and hence, different heights and widths of the support may be readily obtained. The advantage of this, when the device is employed in a baby carriage, is evident as the width of the head-piece may be varied to correspond with the width of the carriage.

The head piece 12 is inserted within a loose seam of a piece of netting 13, the upper portion 14 of which extends rearwardly of the head piece 12 and is gathered together and fastened as at 15.

The netting is then extended forwardly and a flexible elastic band, or tie, 16 is enclosed within a loose seam some distance from the end 17 of the netting. In Figures 1 and 5 this tie 16 is shown in the shape of a loop, while in Figure 2 it is shown as a band, or cord.

In Figure 1, my device is shown as applied to a baby, or child, reclining in a baby carriage. The carriage has the usual basket 18, within which is a mattress 19. A pillow 20 is placed upon the base 10 of the supporting member and the netting 13 is extended over the child, the lower end 17 of the netting falling over the basket 18, and the elastic tie 16 is positioned around the extremity of the basket 18, thus holding and maintaining the netting 13 in position. It is to be noted that the head of the child presses downwardly upon the pillow 20, thus aiding in maintaining the support in an upright position.

It will thus be seen that the netting extends from within the basket 18 at the head support outwardly over the sides of the basket as indicated at 13' in Figure 1 and is attached to the basket by means of the tie 16.

My device thus allows the complete covering of the child by the netting 13 without the netting coming into contact with the child, and hence, any movement of the latter will not displace or dislodge the netting.

The usual method of applying a netting to a baby carriage having a top as 21, is to

raise the top and then drape the netting over the top 21 and around the basket. The raised position of the top is objectionable as it prevents the child from receiving the full benefit of the sunshine, while my device being unconnected with the carriage top can be employed irrespective of the position of the top, and the position of the latter may be changed from time to time, as desired, without interfering with the netting.

The modification of my device shown in Figures 2 and 3 is adapted for a person reclining upon a bed, or cot, and is similar to the form above described except that it has a rod 22 carried by each side of the netting, to maintain the latter in an extended position, and the lower portion of the netting may be affixed to the user, if desired, by tying the tie 16 around the lower portion of the bed or cot.

It will thus be seen that my device is an effective means for positioning a netting around a recumbent person, and that it in-

cludes a head support for the netting and means for affixing the forward position of the netting to prevent accidental displacement, and it is evident that covering material other than netting may be employed.

I do not limit myself to the particular size, shape, number, arrangement or material of parts as shown and described, as these are given simply as a means for clearly describing my invention.

What I claim is:—

In a protective covering device, in combination, a resilient head piece slidable within a recessed base, a recessed base, a netting attached to the head piece and extended rearwardly over the head piece, a rod carried by each lower side of the netting, and a drawing string carried by the forward portion of the netting.

Signed at New York, in the county of New York and State of New York, this 26 day of May, 1926.

LENA KANOWITZ.
